CLAIM

The ornamental design for spectacles, as shown and described.

DESCRIPTION

FIG. 1 is a perspective view of spectacles, showing my new design;

FIG. 2 is a front view thereof;

FIG. 3 is a rear view thereof;

FIG. 4 is a side view thereof;

FIG. 5 is a side view thereof, opposite that of FIG. 4;

FIG. 6 is a top view thereof;

FIG. 7 is a bottom view thereof;

FIG. 8 is an enlarged perspective view of the hinge of FIG. 1;

FIG. 9 is an enlarged side view of the hinge of FIG. 4; and, FIG. 10 is an enlarged top view of a hinge of FIG. 6.

The broken lines shown in the drawings of spectacles are for the purpose of illustrating the environment and form no part of the claimed design.

1 Claim, 10 Drawing Sheets
